CLAIM

The ornamental design for an aisle seat arm rest and trim, as shown and described.

DESCRIPTION

FIG. 1 is a perspective view of an aisle seat arm rest and trim showing my new design in position of use, it being understood that the broken lines are for illustrative purpose only and form no part of the claimed design;

FIG. 2 is an enlarged top plan view thereof;

FIG. 3 is an enlarged bottom plan view thereof;

FIG. 4 is an enlarged left side elevation view thereof;

FIG. 5 is an enlarged right side elevation view thereof;

FIG. 6 is an enlarged front elevation view thereof; and,

FIG. 7 is an enlarged rear elevation view thereof.
